US0D1099448S

(12) **United States Design Patent** (10) **Patent No.:** **US D1,099,448 S**
(45) **Date of Patent:** **** Oct. 21, 2025**

(54) **WAXING MACHINE**

(71) Applicant: **Zhejiang Prulde Electric Appliance Co., Ltd., Zhejiang (CN)**

(72) Inventor: **Chenghao Yang, Zhejiang (CN)**

(73) Assignee: **Zhejiang Prulde Electric Appliance Co., Ltd., Zhejiang (CN)**

(**) Term: **15 Years**

(21) Appl. No.: **29/926,772**

(22) Filed: **Jan. 31, 2024**

(30) **Foreign Application Priority Data**

Sep. 27, 2023 (CN) 202330633869.X

(57) **CLAIM**

The ornamental design for a waxing machine as shown and described.

DESCRIPTION

FIG. 1 is a perspective view of a waxing machine showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in FIGS. 1-7 illustrate portions of the waxing machine that form no part of the claimed design.

1 Claim, 7 Drawing Sheets
